UNITED STATES PATENT OFFICE.

ELEAZER KEMPSHALL, OF NEW YORK, N. Y., ASSIGNOR TO KEMPSHALL SUPPLY COMPANY, A CORPORATION OF NEW JERSEY.

SPINNING-ROLL.

1,074,503.

Specification of Letters Patent. Patented Sept. 30, 1913.

Application filed January 29, 1913. Serial No. 744,978.

To all whom it may concern:

Be it known that I, ELEAZER KEMPSHALL, citizen of the United States, residing at New York, in the county of New York and State 5 of New York, have invented certain new and useful Improvements in Spinning-Rolls; and I do hereby declare the following to be a full, clear, and exact description of the invention, such as will enable others skilled 10 in the art to which it appertains to make and use the same, reference being had to the accompanying drawings, and to letters or figures of reference marked thereon, which form a part of this specification.

15 This invention relates to improvements in spinning machine rolls. In this art I am familiar with rolls composed of rubber and a layer of fabric forming a base, and coated with pyroxylin, but I find in practical use,

20 the rubber and fabric forming the base of the roll so quickly rebounds that when a knot in a thread passes between the rolls, it forces the thread out of alinement, and not infrequently breaks the thread. I am

25 also familiar with rolls having a base formed of felt and leather, but by actual experience such a construction will last, at the most, but a few weeks. The fabric packs or wads in the center, and the leather soon

30 assumes a corresponding shape, and in time the central peripheral portion of the roll becomes concave, and the thread operated upon will not be twisted.

According to my present invention, I propose to use rubber and leather as a base for the roll, so that while the mass will yield when a knot or enlargement on the thread passes between a pair of rolls, it will not destroy or in any manner distort the alinement of the thread.

The object of my present invention is to so construct the roll that while it will yield, it will be slow in assuming its normal position, and will not tend to exert a quick 45 or impulsive action on the thread when an enlargement passes between a pair of rolls, and at the same time the base will be prevented from spreading laterally, and the longitudinal surface of the roll will be maintained in alinement.

Another object of the present invention is to provide a base which will readily become impregnated on its outer surface with a layer of yielding pyroxylin, or other simi-

lar plastic material, so as to form with the 55 base a homogeneous, slow, yielding mass.

In the accompanying drawings: Figure 1 is an elevation of a pair of rolls, one of which is broken away, to illustrate the construction. Fig. 2 is an enlarged detail cross 60 section of one of the rolls.

1 indicates a metal shaft on which is mounted a metal core, 2. The core supports a layer of soft rubber 3, reinforced with fabric, indicated at 3^x. Fitted tightly 65 around the rubber 3, is a thin binder of leather 3^a, which confines the rubber, and serves to protect it and counteract the resiliency. The leather is coated with pyroxylin, or other similar plastic material, indicated at 4, to provide a smooth outer surface.

A roll constructed as described has all the essential yielding characteristics, and yet I successfully overcome the annoyance and expense caused by the breaking, or slipping of the threads. The constituency of the pyroxylin is such that it will sufficiently yield with the leather and rubber, and will not crack. But quick rebounding of the rubber is retarded by the slow yielding action of the leather, and as the two are bound together in a mass, obviously the slow action of the leather when assuming its normal position will in turn cause the pyroxylin to return slowly with it to the normal position.

It is of the greatest importance in a roll such as used in this art that the resiliency be regulated so as to prevent too quick rebound of the mass, and at the same time 90 it is absolutely essential that the surface of the roll be of material possessing a certain amount of flexibility, and yet be of sufficient strength to afford protection to the yielding base. I find a roll constructed of 95 rubber and a binder of leather may be used to decided advantage, in that the life of the roll is considerably prolonged, and while such a construction is effective in certain limits, to obtain the most lasting results I 100 form a coating of pyroxylin on the leather, the pyroxylin or other similar material being of different density than the leather to protect the latter.

As heretofore stated, soft rubber is employed, in preference to felt, so as to maintain the uniform shape of the roll, for obviously the rubber will rebound to normal

position and does not tend to mat or longitudinally expand. Now to preserve these characteristics of the rubber and yet maintain a slow rebounding action to effectually 5 twist the thread and prevent breakage, I have found leather the most appropriate. The leather retards the rebounding of the rubber, and at the same time because of its density, it protects the surface of the rubber 10 against wear, and preserves uniformity of the mass.

What I claim is:

1. A roll of the class described, comprising a hard core, a layer of soft rubber on 15 the core, a binder of leather around the

rubber, and a coating of plastic material on the leather.

2. A roll comprising a hard core, a layer of soft yielding material on the core, a leather binder around the soft yielding material and a coating of plastic material of different density than the leather around the latter. 20

In testimony whereof I have signed my name to this specification in the presence of 25 two subscribing witnesses.

ELEAZER KEMPSHALL.
